TIME DELAY CIRCUIT

Einar H. Holt, Chicago, Ill., assignor, by mesne assignments, to Associated Electric Laboratories, Inc., Chicago, Ill., a corporation of Delaware

Application September 3, 1931, Serial No. 561,017

4 Claims. (CL 177—311)

The present invention relates to a time delay circuit arrangement which has for its function the performance of a certain duty when a specific event takes place for a given interval of time and to continue said performance for a definite period of time after the termination of said event.

The circuit arrangement of this invention has been shown in its preferred embodiment in association with a current distributing circuit, or line, and has for its function the giving of an alarm signal to indicate a cessation of the current flow in that line when the current stops flowing for a period of at least one-tenth of a second, and the maintaining of that signal for a period of three seconds after the current flow has been restored.

In the associated drawing, in which the invention is diagrammatically depicted by conventional symbols, the current distributing line is designated by the reference character L. Bridged across the two conductors of line L is the relay 1 which is energized when current flows in line L and which is deenergized when there is no current flowing therein. This relay 1 has been shown in its energized position, indicating that current is flowing in the line.

When there is a failure in the current flow in line L, relay 1 deenergizes and retracts its armature, thereby at the resting contact of the armature, completing the obvious circuit of slow-to-release relay 2. Relay 2 thereupon operates and at its armature and make contact completes the obvious circuit of slow-to-operate relay 3.

Relay 3 energizes when its circuit is closed and attracts its armatures 4 to 6, inclusive, at its armature 4 connecting conductor 7 to ground thereby completing the circuit of relay 13 by way of normally engaging contacts 15 of dash-pot relay 14, at its armature 5 connecting conductor 8 to ground, thereby completing the circuit of slow-to-release relay 9 by way of normally engaging contacts 15 of dash-pot relay 14, and at its armature 6, opening a point in the circuit of dash-pot relay 14.

Relays 9 and 13 operate when their circuits are closed by relay 3. Relay 9, upon operating, at its armature 10 and 11 makes multiple ground connections to conductors 7 and 8 to hold itself and relay 13 energized independently of relay 3, while at its armature 12, relay 9 closes a point in the circuit of dash-pot relay 14. Relay 13, upon operating, closes the circuit of the device B, which may be any suitable type of signalling, recording, or registering device, to give an indi-

cation of the condition of the current flow in line L.

When the current flow in line L is restored, relay 1 reenergizes and opens the circuit of relay 2, which after an interval deenergizes and opens the circuit of relay 3. Relay 2 has been made slow-to-release in order that relay 3 may be maintained operated if the current flow in line L is only momentarily restored.

Relay 3 deenergizes and retracts its armatures, leaving relays 9 and 13 energized from the ground connections supplied through armatures 11 and 10, respectively, of relay 9. Relay 3 in retracting its armature 6 completes the circuit of dash-pot relay 14 by way of armature 12 and make contact of relay 9.

Dash-pot relay 14 slowly elevates its plunger in the well-known manner. The plunger of relay 14 is so adjusted that three seconds is required for the plunger to be elevated enough to separate contact sets 15 and 16. However, when this occurs, the circuits of relays 9 and 13 are opened, whereupon those relays deenergize, relay 9 at its armature 12 opening the circuit of dash-pot relay 14, and relay 13 opening the circuit of the device B.

Should there be another failure of the current flow before the plunger of relay 14 has separated the contacts of the sets 15 and 16, relay 3 will open the circuit of dash-pot relay 14 and the plunger of that relay will restore without opening the circuits of relays 9 and 13. Thus the circuit of the device B will remain closed.

Relay 3 is so adjusted that at least one-tenth of a second elapses after the deenergization of relay 1 before it operates sufficiently to close the circuits of relays 9 and 13.

From the foregoing it will be appreciated that the arrangement of this invention provides timing means which causes a signal to be given while an event is taking place, but only when such event has taken place for a definite length of time, and which causes said signal to be maintained for a definite period of time after the termination of the event.

The invention having been thus described, what is considered new and is desired to have protected by Letters Patent is pointed out in the claims which follow.

What is claimed is:

1. In combination with a current distributing circuit, a signalling circuit, a relay connected in the distributing circuit energized while a potential is present in the distributing circuit and deenergized whenever a failure of said potential

- occurs, means for closing said signalling circuit, timing means operated by said relay each time it deenergizes for operating the first mentioned means to close said signalling circuit whenever 5 said relay remains deenergized for a given period of time, means operated by said timing means for maintaining said first means operated to maintain said signalling circuit closed, and other timing means operated by said first time means, 10 when said relay reenergizes, to restore said first means and said maintaining means after a predetermined delay to thereby open said signalling circuit.
2. A time delay arrangement comprising a line 15 circuit, a relay connected in the line circuit and energized and deenergized by the presence or absence of potential existing thereon, a second circuit, a second relay for closing said second circuit, timing means operated by said first relay 20 when it deenergizes and maintained operated as long as said first relay remains deenergized, said timing means, upon operating, operating said second relay to close said second circuit whenever said first relay remains deenergized for a 25 given period of time, means operated by said timing means for maintaining said second relay operated to maintain said second circuit closed, and other timing means operated by the first timing means when said first relay re-energizes 30 to restore said second relay to thereby open said second circuit a given period of time after said reenergization.
3. In a current distributing system, a current 35 distributing circuit, a relay in said circuit energized as long as a potential is maintained in said circuit, said relay deenergized whenever a failure in said potential occurs, a signalling circuit, means operating as a result of a deenergization of said relay of a given duration for closing said
- signalling circuit, said means remaining operated throughout the duration of said deenergization to maintain said signalling circuit closed, means operating as a result of the operation of said first means for maintaining said signalling circuit closed upon the restoration of said first means following the reenergization of said relay, and timing means operating as the result of the restoration of said first means for opening said signalling circuit at the end of a definite time period during which said first means remains continuously restored. 5
4. In combination with a current distributing circuit, a control relay in said circuit energized or deenergized according to whether said circuit is energized or deenergized, a signalling circuit, a second relay for closing said signalling circuit, a slow-to-release relay and a slow-to-operate relay energizing as a result of deenergization of a given duration of the control relay for operating 10 said second relay to close said signalling circuit, a maintaining relay energizing as a result of the energization of said slow-to-operate relay for maintaining said second relay operated independent of said slow-to-release and slow-to-operate relays, and a second slow-to-operate relay operatively energizing as a result of the deenergization of said slow-to-operate relay for a definite length of time following the reenergization of said control relay for a corresponding 15 length of time for restoring said second relay and said maintaining relay to open said signalling circuit, said slow-to-release and first slow-to-operate relays cooperating to prevent the operative energization of said second slow-to-operate relay following a deenergization of said control of a duration less than said definite length of time. 20
